LOOM

Conrad Walter Geier, Hazleton, Pa., assignor to
Duplan Silk Corporation, New York, N. Y., a
corporation of Delaware

Application October 31, 1933, Serial No. 695,991

8 Claims. (Cl. 139—336)

The present invention relates to looms and it particularly relates to the control of the beating-up device of looms so as to avoid irregularities in weaving and excessive wear and strain on the loom mechanism due to repeated stoppage and subsequent startings of the loom. In the operation of a loom the warp passes through the heddles of a plurality of harnesses which alternately elevate and depress certain portions of the warp to form sheds through which the flying shuttles are thrown to place a filler or weft thread in position. After the filler or weft thread has been placed in position the reed carried on the lay of the loom moves or beats such weft or filler thread up to the termination or fell of the woven fabric.

The quality and sales value of the fabric largely depends upon the uniformity of the weave and it is desirable that the weft or filler threads be uniformly spaced within the limit of observation in the fabric.

It is therefore important that the beating-up operation be controlled so as to beat up each of the uniform weft threads with the same force and to the same position at the normal fell of the fabric to produce a woven cloth of most satisfactory quality.

During the operation of a loom frequently it becomes necessary to stop the loom because of breakage of the warp or weft threads, due to exhaustion of the filler in the shuttles, in view of derangements of the mechanism, or for numerous other reasons.

If the lay is in its rearmost position or at back center or is moved to such position before starting of the loom when the loom has been stopped, the next filler or weft thread upon being placed within the sheds will be beaten up to the fell by the reed with substantially the same force and momentum as will result from the full throw or swing of the lay.

However, frequently the loom is so stopped that the lay will be in an intermediate position between its foremost and rearmost positions. Then when the loom is subsequently started, the filler or weft thread will not be beaten up by the full stroke or swing of the lay, and a greater space will occur between it and the last filler or weft thread beat-up at the fell with the formation of a crack or a defect in the cloth.

In addition to causing a defect in the fabric a considerable strain and wear occurs upon the driving parts when the loom is started with the lay being in advance of its forward beating-up stroke, since the strain and wear of the beat-up

occurs before the loom and the lay have attained the proper operating speed.

To avoid these difficulties it has been previously necessary to train the weavers to actuate the loom mechanism by hand so as to move the lay back to its back center position before the loom is started after a stoppage. Since this manual operation is quite laborious and involves a loss of time, considerable care and a certain amount of skill on the part of the weaver, who must usually simultaneously attend to several looms, it is often forgotten and neglected, particularly by untrained apprentice weavers, unless the most rigid supervision is had.

To produce, as far as possible, crack-free merchandise even when the loom is started with the lay intermediate position due to negligence or forgetfulness of the weaver to move the lay to its back-center position, it has been attempted in some instances to maintain the lay connectors, clutches, and other elements of the loom in perfect condition and substantially free of all play. With the loom in this condition, the lay will be forced to the proper beating-up position at the fell of the fabric even though the loom be started with the lay substantially off back center. However, to maintain this condition of operation, it is necessary to make most frequent replacements of slightly worn parts and of the clutch linings to eliminate very slight play arising during short running periods.

An object of the present invention is to provide means for assuring a uniform weave of fabric with substantial elimination of cracks in the woven fabric and to avoid excessive strain and wear upon the loom mechanism, even though the loom be frequently stopped and started, without the need of rigidly supervising the loom operators or weavers to make certain that the lay is moved to its back center position and/or without the necessity of most carefully adjusting the mechanism so that it will be in perfect condition and free of all play.

Another object is to provide an attachment for looms which will assure that the lay and/or beating-up device will be in back center position and that the next weft or filler thread will be properly beaten into position by the fell by the full stroke of the lay, which attachment is relatively inexpensive and may be readily attached to looms of standard construction without material alteration thereof.

Other objects will appear during the course of the present specification.

In accomplishing the above objects it has been

found particularly suitable to provide an attachment which will lock the starting levers of a loom when the loom has been stopped with the lay in an intermediate position substantially forward 5 of its back center. This device may be released and the loom may be started, when the loom operator or weaver actuates the lay manually to its rearmost or back center position. During normal operation of the loom the locking device is 10 kept out of connection with the starting mechanism, until the loom is again stopped with the lay off back center position.

The above and other objects will appear more clearly from the following detailed description, 15 when taken in connection with the accompanying drawings, which illustrate several preferred embodiments of the inventive idea.

In the drawings:

Fig. 1 is a diagrammatic side view of the loom 20 with the latch device of the present invention assembled therewith when the loom is operating with the latch unlocked.

Fig. 2 is a side view upon an enlarged scale of the device of the present invention looking in 25 the same direction as Fig. 1 with latch in locked position.

Fig. 3 is a top view of the latch device of the present invention taken in the direction indicated by the arrow 3 of Fig. 2.

Fig. 4 is a side view of the latch device of the present invention similar to Fig. 2 in the position to which it is moved before the lay may be started 30 into operation.

Figs. 5 and 6 are transverse sectional views 35 respectively upon the lines 5—5, 6—6 of Fig. 2.

Referring to Fig. 1 the loom frame 10 is provided with a drive shaft 11 driven through a reduction gear arrangement by a motor (not shown). To the shaft 11 is connected the crank 40 12, a portion 13 of which is held within the split bearing 14.

To the flanges of the split bearing 14 are connected the connector rods 15, which at their forward end are provided with a split bearing connection 16 to a pivot rod 17 on the structure of the lay 18.

The lay is provided with a lay sword 19 which bears upon the lay rocker shaft 20. The lay 18 carries the shuttle box structure 21, the lay bed 50 22 and the reed 23.

At the rear of the loom is carried a suitable warp let-off mechanism (not shown) and at the front of the loom is carried a suitable woven fabric take-up mechanism (not shown). The 55 warp from the take-off mechanism passes through a series of heddles (not shown) which form the sheds 24, the woven fabric being indicated at 25. The lay 18 is shown toward the foremost position of the structure where it is about to beat up the 60 last filler thread, (indicated rather out of scale) at 26, up to the fell or termination 27 of the woven fabric 25.

The flying shuttle (not shown) places the 65 filler thread 26 in position when it is thrown across the sheds 24 with the lay 18 toward the rearmost or back-center position, indicated at 30, the shuttle in its movement being guided by the reed 23 and the bed 22.

During the operation of the loom the motor 70 is preferably continuously rotated and the starting and stopping of the loom is controlled by the shipper lever 31 provided with the handle 32, which lever 31 by a stud actuates the member 33. The member 33 is pivoted at 34 to the 75 loom frame 10.

Pivottally connected at 25 to the lever 33 is the rod 36 which leads to the clutch (not shown) connected to the shaft 11.

The lever 31 is also provided with a lever element 37 pivoted at 38 to the loom frame 10, which element 37 through the linkage 39 and 40 actuates the rod 41 connected to a brake (not shown) also associated with the shaft 11. The hand wheel 42, as well as other mechanism, may be provided for adjusting the lay 18 to its rear-most position when the loom is stopped. 85

As is apparent, if the lay 18 as shown in Fig. 1 is stopped in advance of its rearmost position indicated at 30 so that it will not advance its full stroke before beating up the filler thread 26 into the fell position 27 of the woven fabric 25, the last filler thread 26 will not be beaten up with the same force and effect as the previous filler thread, with resultant formation of a crack, but it is also apparent that the operating mechanism of the loom being subjected to the strain of the beating-up before it has attained its proper operating velocity, will be severely strained and overloaded. 90

To assure that the weaver or loom operator 100 will move the lay back to its rearmost position, the device of the present invention is provided to lock the starting mechanism when the loom is thrown out or stopped, with the lay-off back-center so that the loom cannot be started again 105 until the lay has been moved back to substantially its rearmost position, unlatching the device.

The locking device of the present application is shown in small scale in Fig. 1 and in large scale in Figs. 2 to 6. It consists of a main bar 50 110 which at its rear end is rigidly connected to a sleeve 51 pivotally mounted on the stud 52 extending outwardly from a plate 55. The sleeve 51 is retained in position upon the stud 52 by the split pin 53. The plate 55 is bolted as indicated at 56 to the loom frame 10. 115

The lower edge of the bar 50 is provided with the notches 58 and 57 which cooperate respectively with the latch 60 and the dog 67. The latch 60 and the dog 67 are carried by the element 61 which is provided with a central opening through which passes the brake rod 36. The set-screws 62 enable the block 61 to be adjustably connected to the rod 36. 120

As shown best in Figs. 2 and 4 it will be noted 125 that the front edge 63 of the notch 58 in the bar 50 is inclined rearwardly to cooperate with the correspondingly shaped projection 94 on the latch 60.

To the side of the block 61 is attached the 130 bar 64 by the screws 65. The rear end 66 of said bar is provided with an inwardly directed flange forming the dog 67 which extends within the notch 57. The upper edge 68 of the dog 67 is adapted to contact with the inclined 135 side 69 of the notch 57 as indicated in Fig. 1.

As indicated in Fig. 1 when the loom is operating, the notched arm 50 is elevated from the block 61. However, when the rod 36 is moved rearwardly, upon stoppage of the loom, when the lever 31 will be moved back to the position shown in dotted lines in Fig. 1, the latch 60 and the dog 67 will engage with the notches 58 and 57 of the bar 50. 140

Also connected to the sleeve 51 inside of the 135 latch bar 50 is the arm 70, the upper portion 71 of which is twisted at an angle of 90° to the bottom portion. The upper portion 71 is provided with a tapped hole 72 receiving the screw 73 which is locked thereto by the nut 74. At the 150
